UNITED STATES PATENT OFFICE.

JOHN H. WATERMAN, OF DETROIT, MICHIGAN.

BOILER OR STOVE GRATE.

SPECIFICATION forming part of Letters Patent No. 445,416, dated January 27, 1891.

Application filed November 11, 1889. Renewed October 10, 1890. Serial No. 367,680. (No model.)

To all whom it may concern:

Be it known that I, JOHN H. WATERMAN, a citizen of the United States, residing at Detroit, in the county of Wayne and State of Michigan, have invented certain new and useful Improvements in Boiler or Stove Grates; and I do declare the following to be a full, clear, and exact description of the invention, such as will enable others skilled in the art to which it appertains to make and use the same.

My invention relates to certain new and useful improvements in grates for center-feed magazine stoves or boilers, the construction and operation of which will be understood from the following description, when taken in connection with the accompanying drawings, in which—

Figure 1 is a view in perspective of the grate, together with the rocking mechanism, parts being broken away; Fig. 2, a view from the opposite side, showing the dumping-bar, and Fig. 3 a view in section.

In the drawings, A represents a circular section cast with radiating arms *a*, there being three of such, that segment of the shaking-section of the grate into which the dumping-section is drawn not being provided with such an arm, and a central bearing *b*, as shown, and provided with a number of spikes *c*, properly arranged to stir up the ashes and cut up the clinkers as they are held down on the spikes by the weight of the coal. This grate is cast with a segmental rack *d*, with which a segmental rocking bar *B* meshes, such bar being connected with a suitable handle *C*, the shaking of the grate *A* being thus provided for.

D represents my dome-shaped center or dumping section of the grate, which is cast with suitable openings arranged diametrically opposite each other, and into which suitable pivot-pins *e* are arranged to enter, such pins being attached to one of the cross-bars *a*, and so situated as to be beneath the dumping center section D and thus protected from the fire. This dome-shaped center D is suitably perforated and is cast with a depending arm *E*, which passes down through and into the ash-pit, and is provided with a hole into which a dumping-rod may be hooked.

My dome-shaped dumping center enables me to displace a larger quantity of coal from the center of the grate, thereby more evenly distributing the coal over the entire surface, and from its dome shape it is more easily dumped under a heavy weight of coal, which result cannot be accomplished by the use of the cone-shaped grates now in use. It also carries the clinkers and ashes from the center to the outside, where the spikes are provided to stir up the ashes and cut up the clinkers.

What I claim is—

In a grate, the combination, with shaking-section *A*, provided with arms *a*, bearing *b*, and pivot-pins *e*, mounted upon such arms, of a dumping center *D*, formed with bearings for pins *e*, the parts so arranged that the pins will be beneath the dumping center and protected thereby, as set forth.

In testimony whereof I affix my signature in presence of two witnesses.

JOHN H. WATERMAN.
